WARDROBE SUITCASE

Albert Fiss, St. Louis, Mo.

Application April 27, 1931. Serial No. 533,098

19 Claims. (Cl. 190—41)

This invention relates to wardrobe suit cases; and has special reference to equipment for use in suit cases for holding men's and women's clothing in a manner to prevent the formation of wrinkles and to maintain the clothing in a condition to be worn without re-pressing.

An object of the invention is to provide a conveniently portable luggage case or suit case having therein a hinged frame provided with a folding member around which the garments may be folded in a manner to prevent the formation of wrinkles, and which folding member cooperates with the remaining elements of the invention to prevent the clothing from creeping and from becoming wadded or massed in such a way as to destroy the pressed condition of the clothing. By this construction and arrangement, the clothing is maintained in a freshly pressed condition ready for wear without the necessity of being re-pressed or re-ironed when removed from the case.

Other objects of the invention are to provide improved means for supporting coats and the like and for folding the coats in a way to prevent the formation of wrinkles, and also to provide improved means for supporting women's garments in a way to prevent the formation of wrinkles; to provide attachments for supporting the invention in connection with the suit case in such a way as to obtain the necessary room and space for the invention without interfering with the usual conveniences of the suit case; and to obtain all of the other advantages and useful effects herein disclosed, reference being made to the accompanying drawings, in which—

Fig. 1 is a perspective view of an open suit case containing an embodiment of the present invention.

Fig. 2 is a vertical cross-sectional view of the suit case showing different features of the present invention in operated positions.

Fig. 3 is an enlarged sectional view showing other features of the invention including the device by which the garment holder may be detachably secured in connection with the suit case.

Fig. 4 is a perspective view showing a portion of the frame whereby the garments are maintained in condition for wear without re-pressing.

Fig. 5 is a perspective view of an open suit case showing an attachment for use in supporting women's garments, such as dresses and skirts.

Fig. 6 is a vertical cross-sectional view of a suit case embodying the invention shown in

Fig. 5.

Fig. 7 is an enlarged detail view showing the

construction and arrangement of the hinged frame.

Fig. 8 is a view showing the end of the frame detached from the support to which it is hinged.

Fig. 9 is a perspective view showing a portion 60 of the garment supporting end of the frame.

The case shown in Figs. 1 to 3, inclusive, and in which the present invention is embodied comprises walls forming a body portion 1 having a loop handle 2 pivoted to one side wall thereof and 65 walls forming a top or lid portion 3 having one side connected with the side of the body portion 1 by hinges 4. The hinges 4 connect the top or lid portion 3 with the wall of the body portion 1 that is opposite from the wall to which the handle 70 2 is attached. Locking and latching elements 5 on that wall of the body 1 to which the handle 2 is secured are designed and arranged to be engaged with cooperating locking and latching elements 6 on the corresponding wall of the top or 75 lid 3 in order to hold the suit case closed.

A wall 7 having a length and width approximately equal to the inside length and width of the suit case has its rear edge connected with the rear or hinged wall of the lid 3 by a hinge device 8, which permits the wall 7 to be moved with or independently of the lid 3, as desired. By this construction, the wall 7 may rest flat upon the body portion 1 of the suit case when the lid 3 is opened, or the wall 7 may be moved along 80 85 with the lid 3, or said wall 7 may be moved to any intermediate position.

The wall 7 cooperates with additional walls that constitute a frame in such a way as to form, with said additional walls, a tray or compartment 90. The additional walls mentioned comprise a rear wall 9, side walls 10 having their rear ends connected with the ends of the wall 9, and a bar 11 having its ends attached to the walls 10, or the front ends of said walls 10, by means of angular brackets 12. The lower edges of the walls 10 are designed and adapted to seat upon the marginal portions of the wall 7. The front edge of the wall 7 is hinged to a wall 13 that is designed and adapted to be seated against the upwardly and rearwardly inclined ends 14 of the walls 10. The walls 10 are equipped with flexible latch elements 15 designed and adapted to be engaged with fasteners 16 on the front surface of the wall 13 when the wall 13 is seated against the inclined ends 14 of the walls 10. Thus, the wall 7 may be held in connection with the frame described in such a way as to cooperate with said frame to provide a compartment or tray. 100 105 110

Hinges 17 are attached to the wall 9 and have in connection therewith fasteners 18 designed and adapted to be detachably connected with cooperating fasteners 19 on the hinge extension 8 of the wall 7. Thus, the frame comprising the members 9, 10 and 11 may be hinged to the rear wall of the lid 3 for movement with said lid or independently of said lid. Also, said frame comprising said members 9, 10 and 11 is capable of movement with or independently of the wall 7. In order to move the frame independently of the wall 7, it is necessary only to release the fasteners 15 from the cooperating fastener members 16. As shown, the fasteners 16 are ball elements designed and adapted to be releasably engaged by socket elements 20 on the fastener members 15. A spring bracket 21 is attached to the rear wall frame member 9 in such a way as to be releasably engaged by a frame 22 attached to a coat hanger 23 of conventional or any desired construction. The coat hanger frame 22 may be easily detached from and engaged with the bracket 21 in order to facilitate and expedite the placing of coats 24 and other garments upon or in connection with the hanger and the subsequent attachment of the hanger to the bracket 21, or the removal of the hanger from connection with the bracket 21 to permit the removal of the garments from the hanger.

30 A satisfactory method of use of this invention is to detach the hanger from the bracket 21; place the garments in connection with the hanger in the usual and familiar way; connect the hanger with the bracket 21 so as to prevent the hanger from slipping out of place; fold the garments along the pressed creased lines; detach the wall 7 from the walls 10; raise the frame 9, 10, 11 from the line 7; drape the garments about and against and along the frame member 11 so as to extend the loose ends of the garments backwardly under the forwardly extended portions without the formation of any undesired creases or wrinkles; raise the wall 7 into contact with the walls 10 so as to hold the garments in proper position without the formation of wrinkles and undesired creases; and then attach the fastener members 15 to the fastener member 16 so as to form a tray or compartment in which the garments mentioned are contained and held in proper position to prevent the formation of undesired creases and wrinkles.

35 The invention may be varied as shown in Figs. 5 to 9, inclusive, of the drawings. As there shown, the invention is embodied in a suit case comprising walls forming a body portion 25 having a loop handle 26 pivoted to one side wall thereof, and walls forming a top or lid portion 27 having one side connected with the side of the body portion 25 by hinges 28. The hinges 28 connect the top or lid portion 27 with the wall of the body portion 25 that is opposite from the wall to which the handle 26 is attached. Locking and latching elements 29 on that wall of the body portion 25 to which the handle 26 is secured are designed and arranged to be engaged with cooperating locking and latching elements 30 on the corresponding wall of the top or lid 27 in order to hold the suit case closed.

40 A wall 31 having a length and width approximately equal to the inside length and width of the suit case has its rear edge connected with the rear or hinged wall of the lid 27 by a hinge device 32 which permits the wall 31 to be moved with or independently of the lid 27, as desired.

45 The wall 31 cooperates with additional walls

50 that constitute a frame in such a way as to form, with said additional walls, a tray or compartment. The additional walls mentioned comprise a rear wall 33, side walls 34 having their rear ends connected with the ends of the wall 33, and a bar 35 having its ends attached to the walls 34 by means of angular brackets 36. The lower edges of the walls 34 are designed and adapted to seat upon the marginal portions of the wall 31. The front edge of the wall 31 is hinged to a wall 37 that is designed and adapted to be seated against the upwardly and rearwardly inclined ends 38 of the walls 34. The walls 34 are equipped with flexible latch elements 39 designed and adapted to be engaged with fasteners 40 on the front surface of the wall 37 when the wall 37 is seated against the inclined ends 38 of the walls 34. Thus, the wall 31 may be held in connection with the frame described in such a way as to cooperate with said frame to provide a compartment or tray. Hinges 41 are attached to the wall 33 and have in connection therewith fasteners 42 designed and adapted to be releasably engaged with the hinged extension 32 of the wall 31. Thus, the frame comprising the members 33, 34 and 35 may be hinged to the rear wall of the lid 27 for movement with said lid or independently of said lid. Also, said frame comprising said members 33, 34 and 35 is capable of movement with or independently of the wall 31. In order to move the frame independently of the wall 31, it is necessary only to release the fasteners 39 from the cooperating fastener members 40. As shown, the fasteners 40 are ball elements designed and adapted to be releasably engaged by socket elements 43 on the fastener members 39.

55 A garment holder frame comprising side members 44 and a transverse member 45 is pivotally connected with the walls 34 by brackets 46 attached to the frame members 44 and mounted on pivots 47 opposite the ends of the bar 35. This permits the frame to be folded over into the compartment or tray formed by the walls 33 and 34 in cooperation with the wall 31, or to be turned to any other position, including an outwardly extended position as shown in Fig. 6. In the outwardly extended position shown in Fig. 6, the end portions 48 of the frame members 44 abut against the undersides of the brackets 36 and thus support the frame in its outwardly extended position. This is a great convenience because, in this way, the suit case can be mounted on a table 49, as indicated in Fig. 6, and the garment supporting frame can be extended outwardly and supported in its outwardly extended position to facilitate and expedite the placement and removal of garments.

60 Garments may conveniently be placed on this outwardly extended frame in a manner that is obvious by reference to Fig. 6 of the drawings, after which the frame can be folded over into the compartment. After the frame is folded over into the compartment, the wall 37 may be moved to position against the inclined ends 38 of the walls 34 and attached to said walls 34 by engaging the socket members 43 with the ball members 40. In case the garment is of such length as to require re-folding in order to be placed in the receptacle or tray, this re-folding can be easily effected by the operation clearly indicated in Fig. 5, which consists in raising the front ends of the members 34 so as to permit the downwardly extended ends of the garment to be extended rearwardly upon the wall 31. Thus, the garment is folded additionally against and about

- the bar 35 after which the pivoted frame 44-45 is swung rearwardly and downwardly to complete the placement of the garment in position to permit the wall 37 to be attached to the ends 5 of the walls 34, as already described. The end of the swinging frame 44-45 has disc members 50 attached thereto so as to seat upon the rear portion of the wall 31 and thus support the swinging frame 44-45 in a position so that the garment 10 will not be crushed at any portion or place. On the contrary, the garment is loosely supported, but with sufficient pressure to prevent the garment from slipping out of place and becoming wadded or massed.
- 15 In both forms of the invention shown, the lid of the suit case is equipped with a flexible fastener member 51 having a socket 52 designed and adapted to engage with a fastener member 53 in connection with the wall 7 (Fig. 2) and wall 31 (Fig. 6). Thus, the special compartment embodying the present invention may be supported in connection with the lid of the suit case and moved with the lid of the suit case to open position when access is desired to the lower portion 25 of the suit case. Obviously, detachment of the fastener device 51 from the fastener device 53 will permit the special compartment of the present invention to be swung downwardly onto the body of the suit case.
- 30 Both walls 7 and 31 are detachably connected with the respective suit case lids, so that either suit case may be readily transformed and changed from a suit case adapted for men's clothing, as shown on sheet 1 of the drawings, to a suit case 35 adapted for women's clothing, as shown on sheet 2 of the drawings. Either form of the invention may be detached and substituted for the other so as to change the construction for use with men's clothing to a construction for use with 40 women's clothing, and vice versa.
- It is now clear that my invention provides means whereby various types of garments may be easily transported in suit cases without causing the garments to become wrinkled or to assume any condition unsuitable for wear. Freshly pressed garments may easily be placed in this suit case and maintained in a freshly pressed condition ready and suitable for wear for a considerable period of time.
- 50 The construction and arrangement of the invention may be varied within the scope of equivalent limits without departure from the nature and principle thereof. I do not restrict myself in any unessential respects, but what I claim and 55 desire to secure by Letters Patent is:—
1. In a wardrobe suit case, a series of walls forming a compartment, an element connected with said compartment for supporting garments, a bar extending across said compartment and spaced from one of said walls in position to permit the garments to be folded around said bar, and means pivotally connecting said compartment with the rear of the suit case.
  2. In a wardrobe suit case having a body and a lid hinged to said body, a wall hinged to the inside of the rear of said lid, enclosing walls cooperative with said first wall to form a receptacle, hinges connecting said enclosing walls with the inside of the rear of the lid of the suit case, and means for holding said enclosing walls in cooperative relation with said first wall.
  3. In a wardrobe suit case having a body and a lid hinged to said body, a wall hinged to the inside of the rear of said lid, enclosing walls cooperative with said first wall to form a receptacle,
- hinges connecting said enclosing walls with the inside of the rear of the lid of the suit case, means for holding said enclosing walls in cooperative relation with said first wall, a garment hanger device movable into and out of said receptacle 86 for holding a portion of the garment at the rear of the receptacle, and a fold bar for the garment extending across the front of said receptacle.
4. In a suit case having a body and a lid hinged to the rear of the body, a wall hinged to the inside of the rear of said lid, enclosing walls co-operating with said hinged wall to form a receptacle adapted to be enclosed in the lid of the suit case, detachable means hinging said enclosing walls in connection with the inside of the rear of the lid, and detachable means for holding said receptacle within the lid.
5. In a suit case having a body and a lid hinged to the rear of the body, a wall hinged to the inside of the rear of said lid, enclosing walls co-operating with said hinged wall to form a receptacle adapted to be enclosed in the lid of the suit case, detachable means hinging said enclosing walls in connection with the inside of the rear of the lid, detachable means for holding said receptacle within the lid, and detachable means holding said hinged and said enclosing walls of said receptacle in cooperative relation to each other.
6. In a suit case having a body and a lid hinged to the rear of the body, walls forming a receptacle adapted to be enclosed in the lid of the suit case, detachable means hinging said receptacle to the inside of the rear of the lid, detachable means for holding said receptacle within the lid, detachable 100 means holding said walls of said receptacle in cooperative relation to each other, and a garment folding bar extending across said receptacle.
7. In a suit case having a body and a lid hinged to the rear of the body, walls forming a compartment adapted to be enclosed in the lid of the suit case, hinges holding said compartment in pivoted connection with the inside of the rear of the lid, detachable means for holding said compartment within the lid, and elements in said compartment 115 for holding garments folded in a definite relationship.
8. In a wardrobe suit case having a body and a lid hinged to said body, a wall hinged to the inside of the rear of the lid, enclosing walls cooperative with said first wall to form a compartment, detachable means for holding said enclosing walls in cooperative relationship with said first wall, and means for holding said compartment within the lid.
9. In a wardrobe suit case having a body and a lid hinged to said body, a wall hinged to the inside of the rear of said lid, enclosing walls cooperative with said first wall to form a compartment, means hinging said enclosing walls to the 135 inside of the rear of said lid for movement with or independently of said first wall, and detachable means for supporting said compartment within said lid.
10. In a wardrobe suit case having a body and a lid hinged to said body, a wall hinged to the inside of the rear of said lid, enclosing walls cooperative with said first wall to form a compartment, means hinging said enclosing walls to the inside of the rear of said lid for movement with or 145 independently of said first wall, detachable means for supporting said compartment within said lid, and elements supported within said compartment for supporting garments folded in a prearranged relationship.

11. In a wardrobe suit case having a body and a lid hinged to said body, walls forming a compartment, means hinging the rear of said compartment to the inside of the rear of said lid, a frame 5 hinged within said compartment, and means for supporting said frame extended beyond said compartment. 80
12. In a wardrobe suit case, a bottom wall for a compartment, side walls for said compartment 10 supported in hinged relationship to said bottom wall, a front wall for said compartment hinged to said bottom wall, means for supporting said front wall in cooperative relationship to said side walls of said compartment, a frame, and means 15 pivotally supporting said frame near the front of said compartment for swinging movements rearwardly into said compartment or forwardly to extend beyond said compartment, as desired. 85
13. In a wardrobe suit case, a bottom wall for a 20 compartment, side walls for said compartment supported in hinged relationship to said bottom wall, a front wall for said compartment hinged to said bottom wall, means for supporting said front wall in cooperative relationship to said side 25 walls of said compartment, a frame, means pivotally supporting said frame near the front of said compartment for swinging movements rearwardly into said compartment or forwardly to extend beyond said compartment, as desired, and 30 means for supporting said frame extended forwardly beyond said compartment. 90
14. In a wardrobe suit case, a bottom wall for a compartment, rear and side walls for said compartment pivotally connected with said bottom wall, a front wall for said compartment pivotally 35 connected with said bottom wall, detachable means for holding said front wall in cooperative relationship to said side and bottom walls, and a bar extending between the front portions of said 40 side walls above said bottom wall. 95
15. In a wardrobe suit case, a bottom wall for a compartment, rear and side walls for said compartment pivotally connected with said bottom wall, a front wall for said compartment pivotally 45 connected with said bottom wall, detachable means for holding said front wall in cooperative relationship to said side and bottom walls, a bar extending between the front portions of said side 50 walls above said bottom wall, and means cooperating with said bar to hold a garment in said compartment in proper prefolded arrangement. 100
16. In a wardrobe suit case having a body section and a lid section hinged to said body section, a wall hinged to the inside of the rear of 55 one of said sections, a pair of spaced members mounted between said wall and the top of said lid and each having one end hinged to the inside of the rear of said lid, a bar connecting the op- 105
- posite ends of said members and cooperating therewith to form an open frame, detachable means for securing said wall to said members, and means pivoted to said members adjacent to said bar and cooperating with said bar to form an open frame and being movable from outwardly extended position beyond said bar to position extending from said bar toward the rear of the lid. 110
17. In a wardrobe suit case having a body section and a lid section having its rear portion hinged to the rear of said body section, members forming an open frame hinged to the rear of one of said sections and extending toward the front of the suit case, a wall having its rear edge hinged to the inside of one of said sections for swinging movements with or apart from said members, means detachably connecting said wall with said members, and members hinged to the front end of said frame and cooperating therewith to form an additional frame movable to outwardly extended position beyond said first frame and to position extending rearwardly from the front of said first frame to the rear of the suit case. 115
18. In a wardrobe suit case having a body section and a lid section having its rear portion hinged to the rear of said body section, members forming an open frame hinged to the rear of one of said sections and extending toward the front of the suit case, a wall having its rear edge hinged to the inside of one of said sections for swinging movements with or apart from said members, means for detachably connecting said wall with said members, members hinged to the front end of said frame and cooperating therewith to form an additional frame movable to outwardly extended position beyond said first frame and to position extending rearwardly from the front of said first frame to the rear of the suit case, and means for supporting said second frame in outwardly extended position beyond said first frame. 120
19. In a wardrobe suit case having a body and a lid having its rear portion hinged to the rear of said body, members forming an open frame hinged to the rear of said lid and extending toward the front of the suit case, members hinged to the front end of said frame and cooperating therewith to form an additional frame movable to outwardly extended position beyond said first frame and to position extending rearwardly from the front of said first frame to the rear of the suit case, means for supporting said second frame in outwardly extended position beyond said first frame, a wall cooperating with said first frame to form an enclosure within said first frame, and detachable means for securing said wall to said first frame. 125

ALBERT FISS.
